US00D683063S

(12) **United States Design Patent**
Lopez et al.

(10) **Patent No.:** US D683,063 S
(45) **Date of Patent:** ** May 21, 2013

(54) **LIGHTING FIXTURE**

(75) Inventors: **Peter E. Lopez**, Cary, NC (US); **Aparna Sproelich**, Cary, NC (US); **Jason Taylor**, Cary, NC (US)

(73) Assignee: **Cree, Inc.**, Durham, NC (US)

(***) Term: **14 Years**

(21) Appl. No.: **29/377,926**

(22) Filed: **Oct. 27, 2010**

(51) LOC (9) Cl. **26-99**

(52) U.S. Cl.

USPC **D26/113**

(58) **Field of Classification Search**

(57) **CLAIM**

The ornamental design for lighting fixture, as shown and described.

DESCRIPTION

FIG. 1 is a front isometric view of a first embodiment of a lighting fixture according to the design;

FIG. 2 is a side isometric view of the lighting fixture of FIG. 1;

FIG. 3 is a rear isometric view of the lighting fixture of FIG. 1;

FIG. 4 is a side view of the lighting fixture of FIG. 1;

FIG. 5 is a front view of the lighting fixture of FIG. 1;

FIG. 6 is a rear view of the lighting fixture of FIG. 1;

FIG. 7 is a front isometric view of a second embodiment of a lighting fixture according to the design;

FIG. 8 is a side isometric view of the lighting fixture of FIG. 7;

FIG. 9 is a rear isometric view of the lighting fixture of FIG. 7;

FIG. 10 is a side view of the lighting fixture of FIG. 7;

FIG. 11 is a front view of the lighting fixture of FIG. 7;

FIG. 12 is a rear view of the lighting fixture of FIG. 7;

FIG. 13 is a front isometric view of a third embodiment of a lighting fixture according to the design;

FIG. 14 is a side isometric view of the lighting fixture of FIG. 13;

FIG. 15 is a rear isometric view of the lighting fixture of FIG. 13;

FIG. 16 is a side view of the lighting fixture of FIG. 13;

FIG. 17 is a front view of the lighting fixture of FIG. 13; and, FIG. 18 is a rear view of the lighting fixture of FIG. 13.
